REGENERATIVE COKE OVEN

Filed Jan. 23, 1928

BY

W. F. Bixby ATTORNEY

INVENTOR
Carl Otto

UNITED STATES PATENT OFFICE

CARL OTTO, OF ESSEN-RUHR, GERMANY

REGENERATIVE COKE OVEN

Application filed January 23, 1928, Serial No. 248,940, and in Germany February 28, 1927.

The invention relates to regenerative coke ovens and has in particular reference to a regenerative oven with weak and strong gas supply, such as the oven described in my co-pending application Serial Number 14,472, filed March 10, 1925. If designed as a combined oven, this oven may be fitted with a strong gas supply in the manner employed in the well-known underfire construction.

10 Now the invention refers to an improvement of this oven which is designed as a combined oven, and substantially consists in so arranging the strong gas supply for example, coke oven gas, that the strong gas 15 distributing channels are located below each oven bottom and are adapted to be connected to the gas main or to be shut off therefrom, so that according to the heating direction either only the channels located below 20 alternate or even-numbered oven chambers or only those located under the intermediate or odd-numbered chambers are fed with gas.

In order to allow of the invention to be more easily understood, an embodiment of 25 same is illustrated in the drawings which accompany and form part of this specification.

Figure 1 is a vertical cross section showing the distributing channels below each 30 oven chamber.

Figure 2 is a horizontal section, showing the distributing channels connected to the gas main.

The illustrated embodiment differs from 35 the combined regenerative coke oven described and illustrated in my co-pending parent application substantially in the fact, that the underfire heating is replaced by the strong gas supply which is described in 40 detail in the following.

As will be seen from the drawings, strong gas distributing channels a , a^1 are arranged below each horizontally elongated oven chamber 1, 2, 3, 4 immediately below the 45 bottom of the chamber. Of these channels the channel a is communicably connected by conduits 7 and burners 8 with all odd-numbered heating flues 5 of one heating wall, whilst the other channel, a^1 , is communicably 50 connected by conduits 9 and burners 10 with

all even-numbered heating flues 6 of the neighboring heating wall. The arrangement is such, that according to the heating direction either only the channels a , a^1 , located below alternate of even-numbered oven 55 chambers or those located below the intermediate or odd-numbered ones are fed with gas. Of course, the channels located below one oven chamber might be combined so as to form a single channel. 60

The gas main 13 may be connected by means of a main valve 14 and a valve 15, with conduits 16 and 17. The conduit 16, is connected by means of the valves 18, to each of the distributing channels a , and the conduit 17, is connected, by means of valves 19, with each of the distributing channels a^1 . By means of the valves 18 and 19, strong 65 gas may thus be supplied to the distributing channels located under the even numbered oven chambers, or to the distributing channels below the odd-numbered chambers, as desired. 70

In comparison with the combined regenerative coke oven described in my co-pending parent application the invention affords the advantage of the regenerators being not longer interrupted by the strong gas ascension conduits. As the brickwork between these strong gas conduits and the 75 neighboring regenerator spaces must be made rather thick, to obviate leakages from these strong gas conduits, a considerable 80 undesired reduction of the regenerator space or width of regenerator chamber is caused. 85 With the regenerative coke oven designed according to the invention the regenerator space is notably increased, as strong gas ascension conduits are obviated. Besides 90 this, the further advantage is obtained of 95 any passage of gas from the strong gas distributing channels fed with gas to those shut off from the gas supply is obviated with certainty due to their mutual local separation.

What I claim is:—

In a regenerative coke oven battery, provided with a series of alternate horizontally elongated oven chambers and heating walls therefor, arranged side by side in a row, 100

each heating wall comprising a row of vertical combustion flues, regenerators extending below and in the direction of the oven chambers, strong gas distributing channels 5 located below the bottom of each of said oven chambers and above the regenerators, a strong gas supply main, means for communicably connecting said channels to the main, means for alternately supplying strong 10 gas from said main to the distributing channels located below alternate oven chambers and to the distributing channels located below the chambers intermediate said alternate chambers, and conduits communicably 15 connecting said distributing channels with the heating flues.

In testimony whereof, I have signed my name to this specification.

CARL OTTO.
